(57) **CLAIM**

The ornamental design for a rechargeable halogen lantern with charging base, as shown and described.

DESCRIPTION

FIG. 1 is a front view of the rechargeable halogen lantern with charging base showing my new design;

FIG. 2 is a rear view of the rechargeable halogen lantern with charging base of FIG. 1;

FIG. 3 is a left side view of the rechargeable halogen lantern with charging base of FIG. 1;

FIG. 4 is a right side view of the rechargeable halogen lantern with charging base of FIG. 1;

FIG. 5 is a top plan view of the rechargeable halogen lantern with charging base of FIG. 1;

FIG. 6 is a bottom plan view of the rechargeable halogen lantern with charging base of FIG. 1;

FIG. 7 is a front view of the rechargeable halogen lantern with charging base of FIG. 1;

FIG. 8 is a left side view of the rechargeable halogen lantern with charging base of FIG. 1;

FIG. 9 is a bottom plan view of the rechargeable halogen lantern with charging base of FIG. 1;

FIG. 10 is a perspective view of the rechargeable halogen lantern with charging base of FIG. 1 with a handle portion thereof illustrated in an optional projected position;

FIG. 11 is a perspective separated view of the rechargeable halogen lantern with charging base of FIG. 1, viewed generally from the front and top thereof; and,

FIG. 12 is a perspective separated view of the rechargeable halogen lantern with charging base of FIG. 1, viewed generally from the bottom and right side thereof.
